Specification for Design.

Patented Oct. 7, 1919.

Application filed April 7, 1919. Serial No. 288,394. Term of patent 7 years.

To all whom it may concern:

Be it known that I, BENJAMIN M. SHANKLIN, a citizen of the United States, residing at Springfield, in the county of Hampden and States of Massachusetts, have invented a new, original, and ornamental Design for a Casing for a Strip-Punching Apparatus, of which the following is a specification, reference being had to the accompanying drawing, forming part thereof.

In the drawing—

Figure 1 is a side elevational view of a

casing for a strip punching apparatus showing my new design;

Fig. 2 is a top plan view thereof;

Fig. 3 is a left end elevational view; and

Fig. 4 is right end elevational view.

I claim:

The ornamental design for a casing for a strip punching apparatus, as shown.

BENJAMIN M. SHANKLIN.
